(57) **CLAIM**

The ornamental design for boot sole, as shown above.

DESCRIPTION

FIG. 1 is a bottom perspective view of the boot sole in accordance with the present invention;

FIG. 2 is a bottom view;

FIG. 3 is a side elevational view from the right side of FIG. 2;

FIG. 4 is a side elevational view from the left side of FIG. 2;

FIG. 5 is a front elevational view of FIG. 2; and,
FIG. 6 is a rear elevational view of FIG. 2.

The broken showing a rectangular shape in the arch region, defines the boundary of the design. The broken lines and the area within, form no part of the claim.

1 Claim, 3 Drawing Sheets

FIG. 2

FIG. 3

FIG. 4

FIG. 5

FIG. 6
